ATTORNEY

UNITED STATES PATENT OFFICE.

CHARLES A. RANDALL, OF NEW YORK, N. Y.

TELEPHONIC RECEIVER.

SPECIFICATION forming part of Letters Patent No. 295,804, dated March 25, 1884.

Application filed May 3, 1883. (No model.)

To all whom it may concern:

Be it known that I, CHARLES A. RANDALL, a citizen of the United States, residing at New York, in the county and State of New York, 5 have invented new and useful Improvements in Telephonic Receivers, of which the following is a specification.

This invention relates to an improvement in the type of telephone-receivers shown in my 10 Patent No. 235,021, dated November 30, 1880, in which a diaphragm carries a centrally-projecting soft-iron core which extends loosely into a hollow helix and is acted upon to vibrate the diaphragm by electric currents traversing the helix, the tip of the core being 15 close to a permanently charged stationary magnet, the magnetic action of which upon said core is alternately re-enforced and counteracted by the currents. In the patent above 20 referred to, the core, which is carried by the diaphragm, is magnetized only by the inductive effect of the helix and the stationary magnet.

One object of the present invention is to give the receiver a more sensitive character 25 by charging the movable core by contact with a permanent magnet, so that there will be a much greater normal attraction between it and the stationary magnet than in the old form of receiver, and therefore a more extended and 30 vigorous vibration of the diaphragm when the magnetism of the core of the helix is alternately neutralized and re-enforced by the action of the currents over the helix.

Another object of the invention is to enable the helix of the receiver to be automatically cut out of circuit when not in use, and included in the circuit when the receiver is 35 taken in hand for use.

In the accompanying drawings, Figure 1 is a 40 side view of the telephonic receiver constructed according to my invention. Fig. 2 is a section of the instrument in the plane of the diameter of the helix and longitudinal center of the permanent magnet. Fig. 3 is a detached 45 perspective view of the permanent magnet. Fig. 4 is a sectional view of a modified form of instrument in a plane similar to that of Fig. 2.

The letter A indicates a permanent magnet 50 of horseshoe shape, having one of its holes, as

at a, flattened in the shape of a circular disk, with an opening at its center and its margin projecting slightly, as shown at b, so as to surround a shallow chamber in the outer face of the magnet. Upon the projecting margin b is 55 placed the diaphragm C, outside of which is arranged the mouth-piece D, in the usual manner. To the center of the diaphragm is secured one end of a projecting soft-iron core, E, which extends through the opening in the 60 flattened portion a of the magnet-leg, and has its tip close to the opposite pole of the magnet. Behind the flattened pole a is secured a hollow helix, F, which surrounds the core E, and is to be connected in the receiving-circuit 65 when the instrument is in use in substantially the ordinary manner. In the opposite pole of the magnet from the flattened pole a is arranged an adjustable soft-iron screw, G, which is magnetized by its contact with the 70 magnet, and may have its tip adjusted toward or from the tip of the core E, for the purpose of bringing the operative poles of the magnet into their most effective relation. It will now be readily seen that the core E and screw G, 75 being both magnetized by contact with the permanent magnet, will have such an attraction for each other that the elastic diaphragm C will be normally bowed inwardly with 80 considerable force, and when the electrical impulses of one polarity traversing the helix neutralize the normal magnetism of the core and create a new polarity of the tip of the core the resilience of the diaphragm and the repelling magnetism of G will cause the diaphragm to 85 make an outward half-vibration of certain amplitude and force, and when the current is reversed it will perform another half-vibration back or in an opposite direction to the first with a force much greater than that of the 90 simple attraction of the two poles for each other, from the fact that this inward half-vibration results from the attraction between two magnetic poles of opposite polarity reinforced by the polarization by the current 95 flowing over the helix, instead of the attraction simply of one magnetic pole for an unmagnetized core. In Fig. 4 the core is left off the diaphragm, and the polar screw G is extended into the helix, and may be adjusted in proper 100

proximity to the center of the diaphragm, which, in this modification, represents the opposite pole of the magnet. The action in this modification of the receiver will obviously be similar to that of the first-described form.

- Referring to Fig. 2, the magnet A is mounted upon the end of a handle, H, of non-magnetic material, bored centrally, as shown at h, and having in its lower portion a chamber, h', which is closed by a cap, h². To the outer surface of this cap are secured two binding-posts, i and i', and through said cap extends a metallic rod, k, which is driven inwardly by a metallic spring, k', which surrounds the rod and has one end bearing against the pin k² therein, and its other end bearing against the inner surface of the cap h², the inward movement of the rod being limited by a shoulder, k³, which strikes the outer surface of the cap. Near its inner end an insulating-plate, l, is let into the rod k, and against said rod bears the tip of a metallic finger-spring, m, the opposite end of which is secured to the inner surface of the cap h². The tip of this spring m bears against the metallic portion of the rod k just below the insulating-plate l when the rod is driven inward by its spring, but will bear against said insulating-plate l when the rod is drawn outward, as would be the case when the instrument is suspended by the ring on the outer end of the rod and its weight rests upon and compresses the spring k'. One of the wires, w, which leads from the helix and through the handle, is connected with the binding-post i, and the other wire, w', is connected with the finger-spring m, while the binding-post i' is connected with the metallic spiral spring k', which bears against the metallic pin k² and the rod k. It will now be seen that when the instrument is removed from its usual supporting-hook and the rod k forced inward by the spring k' an electrical current flowing over the main line circuit to the binding-post i will pass over the wire w, the helix F, wire w', finger-spring m, rod k, pin k², spring k', and the connection between it and binding-post i', and from this binding-post off again on the main line, the instrument being thus included in the main circuit. When the instrument is not in use and is suspended by the rod k, said rod will be drawn outward, and the tip of the finger-spring m will rest upon the insulating-plate l, so that the circuit will be broken and the helix cut out. It is very desirable that as little resistance as possible be included in the main line, and by these automatic devices for cutting out and cutting in the instruments I insure the re-

moval from the main circuit of the helices of all receiving-instruments which are not in actual use. A further advantage of these automatic devices is that when the devices are not in use they are placed out of danger of 65 injury by lightning.

Having thus described my invention, what I claim is—

1. In a telephonic receiver, the combination of a permanent magnet having one of its poles formed into a disk integral therewith, and provided with a rim or raised edge forming a support for the vibratory diaphragm, an elastic or vibratory diaphragm secured thereto and arranged to be acted on inductively, and a 70 helix arranged to vary and control the inductive action of the permanent magnet upon the elastic or vibratory diaphragm, substantially as described.

2. In a telephonic receiver, the combination, 80 with the permanent magnet A, having one of its poles flattened or laterally extended and centrally perforated, of the diaphragm secured to the outer margin of said flattened pole, the core projecting from the diaphragm 85 through the opening in the flattened pole and close to the other pole, and the helix loosely surrounding said core, substantially as described.

3. The combination, in a telephonic receiver, of a permanent magnet having one of its poles formed into a disk integral therewith, and having a raised rim or edge for supporting the vibratory diaphragm, an elastic or vibratory diaphragm supported thereon, a soft-iron core or extension attached to or in contact with the other pole of the permanent magnet, and a helix surrounding and adapted to influence such soft-iron core or extension, the thus formed operative poles of the magnet 100 being in magnetically operative proximity to each other, and the helix being arranged to vary and control their magnetic action on each other and the vibratory or elastic diaphragm, substantially as described. 105

4. The combination, with the helix and the handle, of the spring-actuated rod k, provided with the insulating-plate l, the finger-spring bearing against said rod and connected with the helix, and the binding-posts connected, 110 respectively, with the helix and the said rod, substantially as described.

In testimony whereof I have hereunto set my hand in the presence of two subscribing witnesses.

C. A. RANDALL.
